The ornamental design for double-stack multiports for making optical connections, as shown and described.

DESCRIPTION

FIG. 1 is a top perspective view of a double-stack multiports for making optical connections showing the new design; FIG. 2 is a top view of the multiport of FIG. 1;

FIG. 3 is a bottom view thereof of FIG. 1;

FIG. 4 is a right side view thereof of FIG. 1;

FIG. 5 is a left side view thereof of FIG. 1;

FIG. 6 is a front view thereof of FIG. 1; and,

FIG. 7 is a rear view thereof of FIG. 1.

The multiports may have other optional ornamental features relating to the finish of portions of the top surface as desired.
